UNITED STATES PATENT OFFICE

WARREN V. JOHNSON, OF BLOOMSBURG, PENNSYLVANIA, ASSIGNOR TO AMERICAN CAR
AND FOUNDRY COMPANY, OF NEW YORK, N. Y., A CORPORATION OF NEW JERSEY

MINE CAR

Application filed February 17, 1930. Serial No. 429,064.

This invention relates generally to mine cars and contemplates the provision of a mine car having a relatively narrow underframe.

Another object of the invention is the provision of a mine car having a narrow underframe with the wheels arranged outside of the sills thereof and having body supporting elements secured to the ends of the sills, which body supporting elements are adapted to function as bumpers.

Another object of the invention is the provision of a mine car having a welded body.

A further object of the invention is to provide a mine car which is strong and durable in operation and which is easy and simple to manufacture and to repair.

Other objects and advantages of this invention will be apparent from the following description, taken in conjunction with the accompanying drawings, in which

Figure 1 is a top plan view of the car underframe;

Fig. 2 is a side elevation of the car of the present invention;

Fig. 3 is an end view of the car, showing the end gate thereof;

Fig. 4 is a detail sectional view through one end of the car, showing the gate and the gate latching means;

Fig. 5 is a sectional view, showing the car side and a portion of the car floor; and

Fig. 6 is a sectional view, showing the car end and its attachment to the car sides and car bottom.

Referring now more particularly to the drawings, a car of the present invention contemplates certain improvements on the car shown in my prior Patent No. 1,555,982 of October 6, 1925, and comprises generally an underframe A, a body B and the wheels C.

The underframe comprises side sills, indicated at 2, formed of wood or the like and positioned relatively close together, as clearly shown in Fig. 1. The side sills are connected by end sills 4 and project beyond said end sills to form parts of bumper structures, the remaining parts of the bumpers being formed by body supporting blocks, indicated at 6, and arranged externally of the sills 2 at the

ends thereof, said blocks being secured to the sills by bolts 8 which pass therethrough and through the sills and through flanges 10 formed at each end of plates 12 arranged along each side of the end sills. The end sills are connected to the plates 12 by suitable fasteners, such as the bolts 14. The ends of the sills 2 and the blocks 6 are rounded and bumper plates 16 are secured thereto, said bumper plates 16 having their ends flanged, as shown at 17, to lie against the inner surfaces of the side sills and the outer surfaces or sides of the blocks 6, respectively. The bumper plates are secured in position by the before-mentioned bolts 8. For further connecting the side sills 2 and the blocks 6, tie rods 18 are provided having the securing nuts 19 and said tie rods extend from the blocks 6 on one side of the underframe through the blocks 6 on the other side of the underframe, as clearly shown in Fig. 1.

The side sills are further strengthened by a plurality of cross-bearers 20, of which three are shown in the present instance, said cross-bearers being positioned and supported by flanged castings 22 secured by bolts 24 to the side sills. In addition to the cross-bearers, the side sills are further connected together by tie rods 26 which pass through castings 22 which support the central cross-bearer, and said tie rods 26 also secure the spaced body supporting brackets 28 which extend outwardly from the side sills 2 and which are each provided with a flange 30 by which they may be secured by the tie rods, said brackets being arranged substantially midway between the ends of the underframe.

Extending across the side sills and secured to the lower edges thereof are metal plates 34, the side edges of which are flanged as at 36. These plates serve to reinforce the underframe, as will be apparent, and to these plates 34 are secured pedestals 38 by bolts 40 which extend through the side sills and which connect the pedestals with the plates 34. In addition to the bolts 40, the pedestals are further secured to the plates 34 by means of rivets 42. The pedestals are formed with spaced legs 44 to define openings for axles 46 for mounting the wheels C. Connecting the legs

100

44 at their lower ends are pins 45 for an obvious purpose, said pins being secured in any suitable manner, as by means of the cotters 47.

5 For stiffening the underframe and for taking up haulage strains, a tie rod 48 is provided which extends through the several cross-bearers 20 and is fitted with securing nuts 49 at its ends.

10 The draft mechanism for the car comprises a pair of tie rods 50 at each end of the underframe which extend through the end sills and through the adjacent cross-bearer 20, said tie rods being provided with securing nuts 51 having bearing against wear plates 52 on the cross-bearer and against the plates 12 on the end sills. Draw bars 54 extend inwardly through the end sills 4 and are mounted at their inner ends for yielding 20 movement under draft strains. This mounting comprises the transversely extending followers 56 to which the draw bars are connected by pins 58. The followers are mounted for sliding movement on the tie rods 50 and for movement with the draw bars, the draft springs 60 being mounted on the draw bars between the followers and end sills for an obvious purpose. Mounted on the tie rods on each side of the followers are front 30 spacers 62 for preventing abnormal compression of the draft springs, while other spacers 64 are mounted on the tie rods in the rear of the draw bars to define positioning abutments for the followers, as will be apparent; 35 said spacers 64 having bearing against wear plates 65 on the cross bearers and through which rods 50 and 48 extend.

The body B of the car is preferably formed of steel and comprises the sides 66, one end 40 68, a floor sheet 70 and an end gate 72.

The floor sheet may be formed of a single sheet or of several sheets, as desired, and the side edges and one end edge thereof are upwardly flanged as shown at 74 to externally 45 lap the lower edges of the side and end sheets 66 and 68, respectively, and said floor sheet is welded to the side sheets and end sheet as shown at 76. The upper edges of the side sheets 66 and the end sheet 68 are provided 50 with outwardly extending stiffening flanges 67; and for stiffening the sides, vertically arranged channels 69 are welded thereto, as shown clearly in Fig. 5. The end sheet 68 has its side edges marginally flanged as 55 shown at 71 to lap the ends of the side sheets 66, and said flanges 71 are welded to the sides as shown at 73.

The body B is supported on the underframe and rests on the sills and is secured thereto by the bolts 40, which, as before mentioned, secure the pedestals 38 and plates 34; the body resting on the brackets 28 and on the blocks 6, as shown in Fig. 2.

The gate 72 is provided along its upper edge with an internal angle 80, the ends of

which angle are mounted for pivotal movement in the upper ends of stakes 82, the lower ends of which latter are welded to the flange 74 of the floor sheet, as shown at 84. For securing the upper ends of the stakes, the 70 same are welded to the upper flanges 67 of the side sheets 66 of the body.

The lower edge of the gate is flanged first outwardly, as shown at 88, and then upwardly, as at 90, and secured to the gate in such 75 a position that the lower leg thereof rests on the flange 90 is an angle 92, the lower leg of which is welded as at 94 to the upturned flange 90, and the angle itself is welded to the gate in the position shown, as indicated at 80 96; the construction just described furnishing a reinforcing means for the lower edge of the gate, which is in effect a box girder. The ends of the angle 92 project beyond the 85 side edges of the gate to define stops 98 which are adapted to engage the end edges of sides 66 of the body to prevent the gate swinging inside of the body, as will be apparent.

For latching the gate in closed position a chain link arrangement 100 is provided which is connected to a clip 102 welded to the floor of the car body and which has an end link 104 which extends through an opening formed in the gate, as clearly shown in Fig. 4; said link 104 being secured in position by 90 a pin 106 formed at the end of a latch lever 108 pivoted to the gate in a bracket 110. Pivoting of the lever will result in the pin leaving the link 104 and permitting swinging of the gate on its pivot.

Constructed as above, a car of the present invention is well adapted to withstand the rough usage of mining service and may be easily and quickly repaired when necessary. The present car provides a construction in 105 which the wheels are arranged outside of the side sills and the car is constructed cheaply and yet durably. It can be seen that the present construction provides a car underframe in which the car wheels may be arranged outside of the side sills while the underframe is adapted to support a car body of usual dimensions. It will also be apparent that the flanged plates 12 arranged on the inner and outer surfaces of the end sills and 110 which are connected at their flanges to the side sills reinforce and stiffen the car underframe at the ends thereof. It can further be seen that the ends of the underframe are reinforced and protected by means of rigid elements comprising the bumper plates 16 connected to the outer plates 12; this construction providing a metal covering extending entirely across the ends of the underframe.

The drawings show one embodiment of the invention, but it is to be understood that various changes in the form and proportions of the device may be made within the scope 115 120 125 130

of the appended claims without departing from the spirit of the invention.

What is claimed is:

1. A car structure comprising an under-frame having side and end sills, said side sills projecting beyond the end sills and forming parts of bumper structures, body supporting blocks secured to the side sills adjacent the ends of the latter to provide the remainder of the bumper structures, ties between the sills, pedestals secured to the ties, body supporting brackets secured to the sills, and a welded body mounted on the underframe and secured to the ties. 10
2. A car structure comprising an under-frame having side and end sills, said side sills projecting beyond the end sills and forming parts of bumper structures, body supporting blocks secured to the side sills adjacent the ends of the latter to provide the remainder of the bumper structures, ties between the sills, pedestals secured to the ties, body supporting brackets secured to the sills between the ties, and a welded body mounted on the underframe and secured to the ties. 20
3. In a car underframe comprising side and end sills, cross bearers connecting said side sills, tie rods at each end of the under-frame for connecting the end sills with the adjacent cross bearers, draft mechanism yieldingly mounted on the said tie rods, and a longitudinally extending tie rod connecting the cross bearers. 30
4. In a mine car, side sills, end sills, cross bearers connecting said side sills, a tie rod connecting said cross bearers, longitudinally extending tie rods at each end of the under-frame for connecting the end sills with the adjacent cross bearers, draft mechanism yieldingly mounted on the longitudinal tie rods, and means for stiffening the ends of the underframe comprising rigid elements secured to the inner and outer faces of the end sills and having end flanges resting against and secured to the side sills. 40
5. A car structure comprising an under-frame having side and end sills, said side sills projecting beyond the end sills and forming parts of bumper structures, body supporting blocks secured to the outer sides of the side sills adjacent the ends of the latter and providing the remainder of the bumper structures, plates secured to the end sills and flanged to lie against the side sills and connected to the latter for tying the side and end sills together, cross bearers connecting the side sills, a tie rod connecting the cross bearers, body supporting brackets extending outwardly from the side sills, tie rods between said sills and securing the brackets to the latter, ties between the side sills and secured to the lower edges of the latter, pedestals secured to said ties, and a unitary body mounted on the underframe and removable therefrom 50
- as a unit and supported at each corner thereof by said body supporting blocks. 6. In a mine car, end sills, side sills extending beyond the end sills and forming parts of bumper structures, body supporting elements secured to the side sills adjacent the ends of the latter and arranged wholly adjacent the outer side walls thereof, said body supporting elements forming the remainder of the bumper structures, body supporting brackets secured to the side sills intermediate the ends of the latter and projecting outwardly therefrom, and a unitary body mounted on the side sills and secured thereto and supported by the blocks and brackets. 70
7. In a mine car, a body comprising a floor plate having an upwardly extending marginal flange along two sides and one end thereof, side plates welded to the side flanges of the floor sheet and having stiffening channels secured thereto, an end sheet having marginally flanged side edges externally lapping and welded to the side sheets and having its lower edge welded to the end flange of the bottom plate, and an end gate pivotally mounted at the other end of the car. 80
8. A mine car comprising an underframe having side sills, end sills, and ties connecting said side sills, said ties being secured to the lower edges of said side sills, body supporting elements secured to the side sills adjacent the ends thereof and arranged against the outer faces of the side sills, the body supporting elements and the ends of the side sills forming bumper structures, and a unitary body carried by the underframe, secured to the ties and supported by the sills and by the body supporting elements. 90
9. In a car underframe, side and end sills, cross bearers connecting said side sills, said side sills projecting beyond the end sills to form part of bumper structures, and body supporting elements arranged wholly adjacent the outer side walls of said end sills and secured thereto, the forward ends thereof defining continuations of the forward ends of said side sills to form the remainder of the bumper structures. 100
10. In a car underframe, side and end sills, cross bearers connecting said side sills, said side sills projecting beyond the end sills to form part of bumper structures, and body supporting elements arranged wholly adjacent the outer side walls of said end sills and secured thereto, the forward ends thereof defining continuations of the forward ends of said side sills to form the remainder of the bumper structures, and bumper plates arranged over the ends of said side sills and body supporting elements. 110
11. In a mine car, end sills, side sills projecting beyond the end sills to define parts of bumper structures, and blocks secured to the outer side walls of said side sills at the ends thereof having their forward ends arranged 120
- 125
- 130

as continuations of the ends of said side sills to form the remainder of the bumper structures, and metal coverings for the ends of said under frame.

- 5 12. In a mine car, end sills, side sills projecting beyond the end sills to define parts of bumper structures, and blocks secured to the outer side walls of said side sills at the ends thereof having their forward ends arranged
10 as continuations of the ends of said side sills to form the remainder of the bumper structures, flanged plates secured to the end sills and lapping the side sills, and bumper plates connected to the bumper structures and
15 lapping the side sills and flanged plates.

16 In witness whereof I have hereunto set my hand.

WARREN V. JOHNSON.
